GUNNERY CORRECTION DEVICE

Wolfgang B. Klemperer, Los Angeles, Calif., assignor to Douglas Aircraft Company, Inc., Santa Monica, Calif.

Application October 15, 1940, Serial No. 361,213

11 Claims. (Cl. 33—49)

My invention relates to gun sighting apparatus with particular reference to a device for correcting the target lead or, in other words, a device for introducing the correction which must be allowed for the component of travel of a moving target across a line of sight.

With respect to aircraft, the sighting correction required in order to attain reasonable accuracy in hitting a moving target airplane from a moving firing airplane depends upon the relative motion of each craft and the influence of air resistance together with the effect of gravity upon the projectile.

It appears to be practically impossible to obtain all of the necessary parameters for the computation and construction of the complete sighting correction by merely gauging quantities physically or mechanically measurable aboard the firing craft while training one sight upon the moving target and tracking it. As a matter of fact, the only influences that can be completely corrected by the gauging of such physically or mechanically measurable quantities, are the influences of the speed vector of the firing craft imparted to the projectile as it leaves the muzzle of the gun. If these phoronomic influences and the influences of trajectory drop due to gravity are properly introduced into a gun sight correcting mechanism then there remains what has been hereinabove termed the target lead. In my co-pending application, Serial No. 300,789, filed October 23, 1939, and entitled Gun installation, I have disclosed a gun mounting and sighting arrangement particularly adaptable for use in a confined compartment where but little room is available for occupancy by a gunner, the invention being of especial utility with, but not limited to, the tail section, wings, and nacelles of aircraft.

In that application a gun is shown mounted for universal movement in the tail section of an aircraft fuselage and the sight therefor is fixed in order that the gunner may sight the gun through its various possible movements without moving his head. The fixed sight is equipped with a reticle movable in the firing field of the gun and connected for movement with the gun by a cable drive system.

The arrangement of the drive system and the routing of the cables are so designed and calibrated that corrections for tangent error, optical distortion and kinematic and phoronomic errors are incorporated therein and reasonable accuracy is thereby obtained. However, as previously

stated, there still remains the desirability of correcting for the target lead.

It has been proposed to obtain the parameters for this target lead correction from the angular velocity of the tracking motions and a range finder device. However, such sources of correction have several important shortcomings. First, the range is likely to change quickly during an encounter between a target aircraft and a firing aircraft; thus the operation of a range finder during the aiming procedure is an appreciable burden on the gunner in addition to the acts of sighting and tracking. Second, the tracking speed can be picked up correctly only providing the gunner succeeds in holding his sighting bead actually on the target. Whenever he overtravels or lags behind or while he is sluing from one target to another the correction is far off. Third, the mechanical angular velocity between the movable gun and the firing aircraft can furnish the correct pick-up only provided the firing aircraft is not maneuvering, but rather pursues a straight course. Whenever the firing craft is turning, pitching, yawing or rolling, errors are introduced which, unless properly eliminated, spoil the correction.

In order to avoid the above enumerated shortcomings my present invention is designed to feed the proper target lead correction into a gun sight optical system by a method operating on an entirely different principle.

Accordingly, it is the principal object of my invention to feed the proper target lead correction into a gun sight optical system with reasonable accuracy.

Another object of the invention is to easily and simply correct gun sight target lead errors, by a mechanism conveniently controlled by a gunner as an unburdening and natural function as he manipulates a flexibly mounted gun.

Another object is to provide a mechanism for correcting target lead errors in a fixed gun sight adapted for use with a flexibly mounted gun, the mechanism being mounted on and movable with respect to the gun.

Another object is to provide a mechanism for adding target lead correction to a gun sighting device designed for overcoming other distortions and errors.

A further object is to provide a device on a firing aircraft, operable through the maintenance of a relative parallelism between the device and a target aircraft for correcting target lead.

A further object is to provide a target lead correction device adapted to introduce any com-

bination of correction components into a gun sighting mechanism through translational, rotative and otherwise universal movement of the device by a gunner as gauged from the velocity and aspect of a moving target.

Other and further objects will become apparent after a reading of the following description and a study of the drawings in which:

Figure 1 is a side elevation showing an embodiment of my present invention as adapted for use on the gun installation disclosed in my pending application previously set forth, a gunner being shown in phantom and in a normal position for concurrent manipulation of my target lead correction device and a gun.

Figure 2 is a perspective view of the butt portion of a machine gun and showing the installation of my target lead correction device thereon, the device replacing one of the conventional spade grips of the gun.

Figure 3 is a perspective view of a fixed gun sight incorporating a movable reticule together with a cable and drum mechanism for imparting horizontal movement to the reticule in response to horizontal movement of a gun and showing points of connection for my target lead correction device.

Figure 4 is a perspective view of the fixed gun sight of Figure 3 together with the movable reticule and a cable and drum mechanism for imparting vertical movement to the reticule in response to vertical movement of a gun and showing points of connection for my target lead correction device.

Figure 5 is a front elevational view of the movable reticule portion of the fixed gun sight with the cover thereof removed and showing the horizontal and vertical adjustment cable drums.

In Figure 1 I have shown the primary essentials of the invention as installed on a gun which is mounted in the tail section of an aircraft for limited flexibility, for example, to fire in a 60° cone.

The outline of the tail portion of the aircraft is indicated by the numeral 10 and an opening 12 is provided in the right or aft end thereof for the projection of a muzzle 14 of a gun 16 therethrough. Doors or other closure means may or may not be provided to fair in this opening as deemed advisable but inasmuch as that is no feature of my present invention all details with respect thereto have been omitted. The only requirement with respect to the opening 12 and closure means therefor is that they shall permit sufficient movement of the gun muzzle to cover the desired conical field of fire.

The gun 16 is mounted for limited universal movement in a yoke 18 which is in turn attached to the aircraft tail structure 10 by means of a bracket 20. The lower portion of the yoke is journaled to the bracket at 22 for rotative movement about a vertical axis. The gun itself is journaled to the yoke at 24 for rotative movement about a horizontal axis.

Normally, a conventional machine gun is equipped with a right and left hand spade grip at the butt end thereof to be grasped by the gunner for swinging the gun. However, in this invention, the right hand spade grip has been replaced by my target lead correction device, leaving only a left hand grip 26 as shown in Figure 2. Thus, when moving the gun the gunner grasps the grip 26 with his left hand and manipulates the correction device with his right hand.

A gunner 28 is shown in phantom in Figure 1 and for his use in aiming the gun 16, a fixed telescopic gun sight assembly 30 is mounted in a position above the gun in a manner such that the field piece 32 thereof is directed toward the area or field lying to the rear of the tail of the aircraft. The cone space of the angular field of the telescopic gun sight 30 covers slightly more than the field in which the gun may be aimed and fired, thereby making it possible to fire the gun at any point or target which may be brought by the gun sight 30 to the eye of the gunner.

The gun sight essentially comprises a complement of optical lenses including an eyepiece lens system in the eyepiece 34, and also an objective lens system in the field piece 32, with suitable erecting lenses disposed therebetween. Preferably the lenses of the gun sight 30 are enclosed by a suitable housing such as the tubular structure 36 attached to the aircraft structure by means of brackets 38 and 41. A reticule box 40 is shown disposed adjacent to the eyepiece of the gun sight 30. Within the reticule box a reticule is movably mounted so that it may move in or parallel to the focal plane of the eyepiece. Means are provided, as hereinafter described, for moving the reticule so that it will appear in the visual image which passes to the eye of the gunner, in a position to indicate the point in the field at which the gun may be aimed at any time.

As shown by Figure 5, the reticule 42 is carried by a reticule frame 44, which is supported in the box 40. One portion of this frame projects into a horizontal frame 46 in a manner to slide horizontally between the upper and lower bars 48 thereof. Another portion of the frame 44 projects into a vertically elongated frame 50 in a manner to be slidable vertically along the bars 52 of such frame. The horizontally elongated frame is engaged by a vertical right-hand threaded screw 54 so as to be moved vertically in either direction from the position in which it is shown in the drawing. A horizontal left-hand threaded screw 56 engages the vertically elongated frame 50 and may be operated to move the frame horizontally in either direction from the centralized position thereof shown in the drawing. These screws 54 and 56 are supported by suitable anti-friction bearings 58 and 60 so as to project within the box. It will be seen that when the screw 54 is rotated, vertical movement of the frame 46 will move the reticule frame 44 in vertical direction and such reticule frame will slide along the vertical bars 52. When the screw 56 is rotated, the vertically elongated frame 50 will move the reticule frame 44 along the horizontal bars 48 of the frame 46. Accordingly, by operation of screw 54 or screw 56 the reticule 42 may be moved either vertically or horizontally, or by a simultaneous rotation of the screws 54, 56 the reticule may be moved in any angular direction between vertical and horizontal.

In order to provide means for rotating the screws 54, 56 in accordance with the vertical and horizontal components of the movement of the gun 16, cable drums 62 and 64 are fixed to the exposed ends of the screws 54 and 56. The drums are then wound by cables from individual cable systems 66 and 68; cable system 66, shown in Figure 3, tying in with drum 62; and cable system 68, shown in Figure 4, tying in with drum 64. Each cable system includes a plurality of

pulleys and a driving drum, the latter being rotated in response to movement of the gun 16.

For example, the driving drum 10 of cable system 66 may be mounted on the gun yoke 18 somewhat on the order of the showing of Figure 1 and geared in a suitable manner as shown in Figure 3 to rotate in response to horizontal movement of the gun. On the other hand, the driving drum 72 of cable system 68 may be mounted on the side of the gun yoke 18, as shown in Figure 1, and also geared in a suitable manner as shown in Figure 4 to rotate in response to vertical movement of the gun.

The routing of the cable systems, contour of the cable drums and gearing of the driving drums are necessarily designed and calibrated to impart movement of the reticule 42 corresponding to movement of the gun 16 and to introduce the required corrections therein for tangent error, distortion and kinematic and phronomic errors. A disclosure of the details and problems connected with this design and calibration has been included in my co-pending application and it has been my purpose here to repeat only such details of my previous invention as are necessary to afford a clear understanding of the present invention.

Accordingly, I will now explain the features and operation of the new device as it may be incorporated with the previous invention.

It has been mentioned that it is proposed to install the target lead correction control on the butt end of the machine gun 16 in place of the right hand spade grip. This is best shown in Figure 2 wherein a gimbal ring 80 is pivoted for rotation on a vertical axis between a pair of brackets 81 extending from the gun 16. Within the ring 80, through the center thereof, is placed what may be termed a vector handle 82 and this handle is mounted for rotation in an elongated threaded collar 84. The collar is in turn pivoted to the ring 80 on a pair of stub shafts 86 which lie in a position normal to the vertical rotative axis of the ring.

The handle 82 is shaped on the order of a pencil and, by its mounting, it is capable of universal articulation. A portion of the handle is provided with a long pitch screw thread at 88 in order that it may be rotated by the gunner and thus caused to move fore and aft with respect to its correspondingly threaded mounting collar 84. Toward the left end of the handle, that which is grasped by the gunner's hand, a small excrescence or finger 90 is provided which will indicate to the hand the amount in which the handle has been turned on its screw thread.

On the right end of the handle 82 there is universally pivotally mounted a button shaped fitting 92 to afford attachment for cables 94, 96, 98, 100 at perpendicular diametrically opposite points on the periphery of the button. The cables are of the Bowden type adapted to extend through casings 102, 104, 106, 108 respectively. The casings are fixed to the butt of the gun 16, being held in proper positions with respect to the button fitting 92 by a bracket 110 bolted to the gun butt at 112 and a bracket 111 fixed to bracket 81 at 113. The bracket 110, in the embodiment shown, attaches to one side of the gun and has a plurality of arms for supporting casings 104, 106, and 108. Bracket 111 supports casing 102. Each of the supporting means is disposed so that the casing held thereby is routed in a manner to assure the absence of binding.

The cables extend from the fixed attachments on the gun to fixed attachments on the tail structure 10 of the aircraft. These fixed structural attachments are indicated by the brackets 114 and 116 in Figure 3 and the brackets 118 and 120 of Figure 4. An ample allowance of slack cable is allowed between the gun and structural attaching points in order to permit the required movement of the gun 16 on its horizontal and vertical axes.

Referring now to Figure 3, continuation of the Bowden cables 94 and 96 of Figure 2 are shown as they tie into the reticule driving cable system 66. Cable 94, after passing the structural casing attachment bracket 114, terminates at 122 in one end of a clevis-type pulley carrier 123 in which are fixed the axle shaft 124 of a floating pulley 126, and the axle shaft 130 of a floating pulley 132. Cable 96, after passing the structural casing attachment bracket 116 terminates at 128 in the other end of the pulley carrier. The routing of the Bowden cables is such that they approach each other in the same plane from opposite directions. The two floating pulleys 126 and 132 are secured in fixed relation to each other by the pulley carrier 123 which holds them spaced from one another.

With reference to Figure 4, the continuation of the Bowden cables 98 and 100 of Figure 2 is almost identical with that just described for cables 94 and 96. In Figure 4 they are shown as they tie into the reticule driving cable system 68. Cable 98, after passing the structural casing attachment bracket 120, terminates at 136 in one end of a clevis-type pulley carrier 142 in which are affixed the axle shaft 138 of a floating pulley 140, and the axle shaft 144 of a floating pulley 146. Cable 100, after passing the structural casing attachment bracket 118, terminates at 145 in the other end of the pulley carrier. The routing of the Bowden cables, as before, is such that they approach each other in the same plane from opposite directions. These two floating pulleys 140 and 146 are also secured in fixed relation to each other by the pulley carrier 142 which holds them spaced from one another.

Thus far, I have described the component parts of my target lead correcting device which cooperate to influence the reticule driving cable systems 66 and 68. I will now discuss the operation of these parts as controlled by the gunner 28 to obtain target lead correction as he sights and manipulates the gun 16.

The gunner grasps the left portion of the pencil shaped handle 82 with his right hand in a similar manner to that shown in Figure 1, and grasps the spade grip 26 of the gun with his left hand in order to move the gun about. If he permits the handle 82 to remain in its neutral position shown no movement will take place in the Bowden cables, the slack mentioned between the gun and tail structure attachment points permitting unhampered movement of the gun. If he displaces the handle from its neutral position however, a displacement of the cables will take place which will react on one or the other or both cable systems 66, 68, depending upon which way the handle 82 is moved. For example, if the gunner raises his end of the handle, the opposite portion will swing downward, pulling on the Bowden cable 98 which will in turn displace the floating pulleys 140 and 146 of cable system 68 and consequently influence the movement of the reticule 42 inasmuch as movement of the float-

ing pulleys relative to the cable system driving drum 72 will cause a slight rotation of the reticule cable drum 64.

Similarly, any movement of the handle 82 from neutral will displace one or more of the cables depending upon the direction of motion and will cause a movement of the reticule in addition to that normally imparted thereto by the driving drums 70 and 72.

In order to produce an excursion proportionate to the target speed component for various target air speeds I provide a variable leverage of the Bowden cable pick-up point 92 with respect to the universal joint axes 86. The larger this leverage, the greater the movement of the pick-up point for any given angular displacement of the handle 82. Adjustment of this leverage is accomplished by rotating the handle 82 about its longitudinal axis in clockwise or counterclockwise direction so that by virtue of its long spiral thread 88 it moves in or out. With the handle withdrawn to its limits the device is adjusted for minimum target air speed. With the handle screwed fully in the leverage is maximum and the device is adjusted for the maximum anticipated target air speed. It must be understood that the end brackets of the Bowden cable must be sufficiently far away from the drum fitting 92 that the latter's movement around an arc or around the axis of the handle will not cause excessive length variation in the two opposing cables attached to the drum or else suitable measures must be provided to control the average cable tension.

In combat operation, the gunner sights his target in the telescope 30, then, assuming that he is aiming at a moving target airplane he manipulates the handle 82 of the target speed correction device so that its direction appears parallel to the direction of motion of the target craft. Tests have shown that but little practice will be required for the gunner to become adept at directing the handle, moving it continuously so that it feels parallel to the fuselage of the target craft as the latter appears in the field of vision, without having to glance at the handle. The accuracy of parallelism may be somewhat limited by feel and estimate but the first order target speed influence can readily be represented.

The universal mounting of the handle 82 is preferably such that movement of the handle is limited to a reasonable cone with respect to the member upon which the device is mounted. The arrangement must merely suffice to cover the most important combat configurations in which the target craft's path makes a moderate angle with either the flight path of the firing craft or the sighting line as the case may be. For such a limited firing cone it appears satisfactory to mount the device in place of one of the spade grips as shown in Figures 1 and 2. For gun installations in rotatable turrets sweeping large spherical angles and equipped with gun sights embodying periscopic features, it may be preferable to support the fulcrum of the articulated handle on the turret structure rather than mounted directly on the gun.

The forward and aft movement of the handle 82 is, as stated, for the purpose of reproducing estimated changes in the target craft's air speed. In order to obtain the proper correction, it is necessary that the button fitting 92 to which the Bowden cables attach be located at a distance from the universal mounting of the handle which is proportional to the target air speed, then

the excursion of the pick-up point of the cables on the button fitting with respect to the handle axis is always directly proportional to the proper target lead correction for any target moving through the air parallel to the longitudinal axis of the handle.

The small excrescence or finger 90 on the handle 82 serves as a pointer indicating the speed to which the device is set. As the gunner rotates the handle clockwise the little finger 90 in moving through approximately one complete revolution would represent an adjustment of the target speed value from, say, two hundred to four hundred miles per hour. Thus the speed adjustment can be made with one hand by feel only without having to look at the handle. The target speed, to be sure, has to be estimated by the gunner knowing the target craft's and his own speed approximately. However, he should have no difficulty in at least hitting the proper order of magnitude, as he perceives in the gun sight whether the target is gaining or falling back with respect to his own craft.

As the handle 82 is manipulated, the horizontal Bowden cables 94 and 96 will pick up the first order component of the horizontal excursion of the button fitting 92 and the vertical Bowden cables 98 and 100 will pick-up the corresponding vertical excursion component. The influence of the Bowden cables upon the reticule mechanism through the loose pulley arrangement remains unchanged for any fixed position of the target speed correction device. Any correction dictated by the device is added to or subtracted from the reticule movement introduced by the gun swivel mechanism through the drive pulleys 70, 72.

In order to further simplify the gunner's job, it is possible to relieve him of automatic variation of the target craft's speed with the attitude of the target craft. The craft will gain speed as it dives and lose speed as it climbs. A first order correction for this influence can be calculated and obtained by placing the vertical Bowden cable anchorage at some angle with the flight axis of the handle 82, or by rocking the gimbal ring 80 in which the handle is mounted on a cam cradle.

While I have herein shown and described my invention in its present preferred embodiment, it will be apparent to those skilled in the art to which it appertains that the essence of the invention lies in influencing, in accordance with the estimated speed vector of the target, the sighting indication to the gunner so that it is moved out of synkinesis with the travel of the gun in the field of fire in the approximate amount necessary to introduce correction to compensate for target lead. Accordingly, after understanding the invention, various changes and modifications may be made therein without departing from the scope thereof as set forth in the appended claims.

The word "synkinesis" is used herein to describe that relationship between the movements of two bodies characterized by a constant relative position of a significant character. Thus the reticule movement is in synkinesis with the gun movement when the reticule indicates on the visual image of the sight the point at which the gun is aimed wherever the gun is directionally moved. The word "ecsynkinate," as used in connection with a previously specified synkinesis, is a word coined to describe the act of effecting a new relationship of movement between two

bodies previously in synkinesis of a specified character which is not characterized by that synkinesis.

I claim:

1. In a correction device for use on a military vehicle, a gun sight fixed to said vehicle, a movable gun, a reticule movable by aiming movements of the gun relative to the optical axis of the fixed gun sight for indicating to a gunner the point at which the gun is aiming in its field of fire, mechanism connecting the reticule to the gun for synkinetized movement therewith, and extraneous means connected to the reticule moving mechanism and operable by the gunner in accordance with the direction of relative target motion to synchronize movement of the reticule with respect to the gun as the gun traverses its field of fire.

2. In a correction device for use on a military vehicle, a gun sight fixed to said vehicle, a movable gun, a reticule associated with the fixed gun sight and movable by aiming movements of the gun relative to the optical axis of the fixed gun sight for indicating to a gunner the point at which the gun is aiming in its field of fire, mechanism connecting the reticule to the gun for movement therewith, a universally movable handle adapted to be grasped by the gunner and manipulated in a manner such that its longitudinal axis is maintained substantially parallel to the direction of motion of a target, and means connecting said handle and said mechanism whereby any movement of the handle adds to or subtracts from the normal movement of the mechanism effected by movement of the gun.

3. In a correction device for use on a military vehicle, a gun sight fixed to said vehicle, a movable gun, means within the fixed sight movable relative to the optical sight axis by aiming movements of the gun for indicating to a gunner the point at which the gun is aiming in its field of fire, a single universally fulcrumed handle mounted for movement with the gun and with respect thereto, said handle being adapted to be manipulated in a manner such that its longitudinal axis is maintained substantially parallel to the direction of motion of a target in the gun's field of fire, means to transmit movement from said handle to said indicating means extraneous of the movement effected by said gun, and means for changing the position of said handle with respect to its fulcrum to increase or decrease its degree of influence upon the indicating means in accordance with the estimated velocity of the target.

4. In a correction device for use on a military vehicle, a gun sight fixed to said vehicle, a movable gun, means within the fixed sight movable relative to the optical sight axis by aiming movements of the gun for indicating to a gunner the point at which the gun is aiming in its field of fire, and a single means universally swingable about a pivot for moving the first named means out of synkinesis with the gun and movable axially with respect to its pivot to vary the degree of influence exerted over the first named means in accordance with the estimated velocity of a target at which the gunner is aiming.

gimbal for universal movement about the fulcrum and for axial movement with respect thereto, articulated means attached to one end of said handle, and mechanism connected to said articulated means and to said movable means within the fixed sight for transmitting motion to said movable means in response to any displacement of said universally mounted member both with said gun and with respect thereto.

15 gun sight, a reticule movable in a plurality of directions within said two sliding means as controlled by relative movement of said two sliding means, means to move said horizontally sliding means in correlation with azimuthal movement

20 of the gun, means to move said vertically sliding means in correlation with elevational movements of the gun, and means to introduce sighting corrections between the movement of the gun and the movement of said horizontally and vertically

the movement of said horizontally and vertically sliding means, said correction introducing means including a manually controlled universally articulated lever adapted to be manipulated parallel in space to the path of a moving target as seen through said optical system.

7. In an aircraft having a movable gun, a gun sight including an optical system fixed in said

30 sight including an optical system fixed in said aircraft, a horizontally sliding means and a vertically sliding means mounted within said fixed gun sight, a reticule movable in a plurality of directions within said two sliding means as con-

35 trolled by relative movement of said two sliding means, means to move said horizontally sliding means in correlation with azimuthal movement of the gun, means to move said vertically sliding means in correlation with elevational

sliding means in correlation with elevational movement of the gun, means to introduce sight corrections between the movement of the gun and the movement of said horizontally and vertically sliding means, said correction intro-

45 universally articulated lever adapted to be manipulated parallel in space to the path of a moving target as seen through said optical system.

and means associated with said lever to vary the amount of introduced correction in accordance with the estimated air speed of the target.

8. In an aircraft having a movable gun, a gun sight including an optical system fixed in said gun.

55 gun sight, a reticule movable in a plurality of directions within said two sliding means as controlled by relative movement of said two sliding means means to move said horizontally sliding

means, means to move said horizontally sliding means in correlation with azimuthal movement of the gun, means to move said vertically sliding means in correlation with elevational movement of the gun, means to introduce sighting cor-

rections between the movement of the gun and the movement of said horizontally and vertically sliding means, said correction introducing means including a lever pivoted to said gun for moving

ment both with and with respect thereto, said movement with respect thereto being always parallel to the direction of movement of a target as viewed in said fixed gun sight, a cable system interconnecting said lever with each of said gun sight sliding means for imparting additional movement to either or both of said means in accordance with the movement of said target, and means for changing the position of said lever

with respect to its pivot to vary in accordance with the estimated target speed the degree of additional movement originally imparted to said sliding means.

9. In an ordnance device for use on a military vehicle, a gun mount, a gun universally directably mounted thereon, a gun sight stationarily related to the mount, a reticule for the gun sight capable of movement in any direction relative to the optical axis of the gun sight, energy transmitting means connecting the gun and reticule for effecting such a synkinesis of the aiming movements of the gun with the said movements of the reticule as to indicate to the gunner the point at which the gun is aiming in its field of fire, means modifying the action of said energy transmitting means to give to the reticule a displacement in any direction with respect to the positions of said synkinesis, and a manual operating control for said modifying means comprising a member capable of being universally directionally displaced from a neutral directional position with reference to the gun to maintain the member in estimated parallelism with the direction of relative movement of the target, said modifying means being controlled by said member to effect said reticule displacement in the

opposite direction from that of the said displacement of said member and of a magnitude having a direct substantially factorial relation to that of the angle of said directional displacement of said member from said neutral position.

10. The combination defined in claim 9 and in addition thereto means under the control of the gunner for adjusting said modifying means to vary the factor of said relationship to compensate for the estimated speed of said moving target.

11. In a correction device for use on a military vehicle, a gun sight fixed to said vehicle, a movable gun, means within the fixed sight movable relative to the optical sight axis by aiming movements of the gun for indicating to a gunner the point at which the gun is aiming in its field of fire, a member mounted on said gun for universal directional movement relative thereto, articulated means attached to one end of said member, and mechanism connected to said articulated means and to said movable means within the fixed sight for transmitting motion to said movable means in response to any directional displacement of said universally mounted member

WOLFGANG B. KLEMPERER.
